Accurate Products, Inc., Indianapolis, Ind., a corpora-
tion of Indiana

Filed Dec. 31, 1962, Ser. No. 72,997

Term of patent 7 years

(Cl. D52—6)

Fig. 1.

Fig. 2.

Fig. 3.

FIG. 1 is a front elevational view of a vehicle gage unit showing my new design.

FIG. 2 is a top plan view of the vehicle gage unit of FIG. 1.

FIG. 3 is a right-hand end elevational view of the vehicle gage unit of FIG. 1.

The appearance of the left-hand end is the same as that of the right-hand end and the appearance of the bottom is the same as that of the top. The back of the unit is without ornamentation.

The essential features of the design reside in the portions shown in solid lines.

I claim:

The ornamental design for a vehicle gage unit, sub-
stantially as shown and described.
